Primary Examiner — Kelley A Donnelly(74) *Attorney, Agent, or Firm* — Polsinelli PC(57) **CLAIM**

The ornamental design for an organizing device, as shown and described.

DESCRIPTION

FIG. 1 is an isometric view of an organizing device showing our new design.

FIG. 2 is another isometric view of the organizing device.

FIG. 3 is a top view thereof.

FIG. 4 is a bottom view thereof.

FIG. 5 is a left side view thereof.

FIG. 6 is a right side view thereof.

FIG. 7 is a front view thereof.

FIG. 8 is a back view thereof; and,

FIG. 9 is a cross-sectional view of the organizing device taken along the line 9-9 shown in FIG. 3 showing a relationship of a liner within a tray.

The broken lines shown in the Figures show portions of the organizing device that form no part of the claimed design. The shade lines in the Figures show contour and do not claim surface ornamentation or treatment.
